SWINGING WINDOW

Martin Lindish, Wyandotte, Mich.

Application September 12, 1936, Serial No. 100,402

4 Claims. (Cl. 20—45)

This invention relates to swinging windows and the object of the invention is to provide a window in which the sash guides are hinged at the top of the window frame and arranged to be swung inwardly with the sash therein to allow cleaning of the window from the inside of the building.

Another object of the invention is to provide a swinging window in which the sash guides are hinged at the top of the window frame and are arranged to be swung inwardly, the sash guides and weights being arranged so that the sash may be withdrawn from the guides when the guides are swung inwardly and will automatically disengage from the sash cords as they are withdrawn from the sash guides.

Another object of the invention is to provide an arrangement whereby the sash upon being re-inserted in the sash guides and moved upwardly will automatically re-engage the sash cords so that the sash will be counterbalanced by the sash weights.

A further object of the invention is to provide a swinging window arranged so that a storm window or screen may be inserted in place in the window opening from the interior of the building.

These objects and the several novel features of the invention are hereinafter more fully described and claimed and the preferred form of construction by which these objects are attained is shown in the accompanying drawings in which—

Fig. 1 is an elevation of a swinging window embodying my invention as it appears from the interior of the building.

Fig. 2 is an enlarged side elevation of the window frame showing the sash weights, cords and pulleys.

Fig. 3 is an enlarged section taken on line 3—3 of Fig. 2.

Fig. 4 is an enlarged section taken on line 4—4 of Fig. 1.

Fig. 5 is an enlarged section taken on line 5—5 of Fig. 2 and showing the engaging means between the sash and sash cord.

Fig. 6 is a view similar to Fig. 5 showing the sash disengaged from the sash cord.

Fig. 7 is an enlarged section taken on line 7—7 of Fig. 1.

Fig. 8 is an enlarged section taken on line 8—8 of Fig. 1.

The window frame 1 shown in Fig. 1 is formed to provide a frame about the usual window open-

ing and is provided with a cross piece 2 across the top of the window opening as shown in Fig. 8. The sash guides 3 and 4 are connected at the top by a cross piece 5 which is hinged by means of the hinges 6 to the cross piece 2 at the top 5 of the window frame. This provides an inverted U-shaped frame in which the cross piece 5 forms the connecting member. This U-shaped frame may be swung as a unit on the hinges 6 shown in Figs. 1 and 8. The sash guide 3 is formed 10 of sheet metal and is shown more particularly in Figs. 7 and 8 and this guide is provided with a parting stop 7 and a trim stop 8 extending longitudinally thereof. The sash guide 4 is a duplicate of the sash guide 3 and it will be noted 15 that the inner edge 9 of each sash guide is out-turned to provide a channel for the upper sash while the lower sash is positioned between the trim stop 8 and the parting stop 7. When in position for use as shown in Fig. 1, the sash 20 guides 3 and 4 engage behind latches 10 which hold the sash guides in place in the window frame.

As will be understood from Fig. 5 a bracket 11 is attached to the upper corner on each side of the inverted U-shaped sash retaining member and each bracket 11 carries pulleys 12 for the sash cords 13 and also a roller 14 over which the cords extend. It will also be noted from Figs. 2 and 5 that the window frame is cut out 25 at 33 to allow the pulleys to turn with the inverted U-shaped sash retainer. The cord 13 extends downwardly and about a pulley 15 on a sliding sash weight 16 shown in Figs. 2 and 3 and this sash weight rides in guides 17 provided therefor 30 on the window frame. Each end of the sash cord is attached to a sash engaging latch 18 shown more particularly in Fig. 6 which is provided with a flat spring 19 on the side thereof and with a latch end 20 which is triangular in 35 form. In the normal position shown in Fig. 5, this latch end 20 engages beneath a shoulder 21 provided therefor in the sash and having a pocket 22 into which the end 20 may be positioned. It is also to be noted that the sash 40 guide 3 is provided with an aperture 23 into which the latch end 20 may move when the parts are in the position shown in Fig. 6. The cord 13 extends from the latch for the lower sash over the pulleys 12 and 14 thence downwardly and about the pulley 15 and thence upwardly again over the pulleys 12 and 14 and 45 downwardly to the sash engaging latch for the upper sash. By this arrangement, a single sash weight is provided for both sash and as this con- 50

struction is duplicated on opposite sides of the window the sash may be properly counterbalanced.

As shown in Fig. 8 a plate 24 is provided on each side of the window frame and an arm 25 is provided which is pivotally connected to the sash guide at 26 and is also provided with a lug 27 riding in the slot 28 on the plate 24. This limits the inward movement of the sash guides 10 on the hinges 6 when the sash are swung inwardly. Also to prevent the sash from falling out of the sash guides after being disengaged from the sash weights, flat springs 29 are provided in each sash guide which form yielding stops for the sash. Also, at the lower end the sash guides are connected by a cross member 30, shown in Figs. 7 and 8, which tends to prevent the sash guides from spreading apart when swung out of the window frame.

When it is desired to clean the glass panes, the latches 10 are drawn downwardly and the lower sash 31 is raised sufficiently to clear the window sill 32. At this time, the sash guides with the sash therein may be swung outwardly to the position shown in Fig. 8. This allows the user to wash both sides of the glass panes in this position, if desired.

However, when swung out to this position the sash may be drawn downwardly as will be understood from Figs. 5 and 6 and withdrawn from the sash guides. In the position shown in Fig. 5 the latch end 20 engages the shoulder 21 and is drawn downwardly with the sash. As the sash comes to position so that the latch end 20 is opposite the aperture 23 in the sash guide the spring 19 moves the end 20 into the opening 23 allowing the sash to be drawn downwardly and disengaged from the sash weight. At the same time, the latch end 20 engaging in the aperture 40 23 will remain in position and hold the sash weight from falling.

Thus, both sash may be readily withdrawn from the guides and washed. Subsequently the sash may be again inserted in the guides and moved back to the position shown in Fig. 6, at which time, the edge 32 on the sash will engage the lower end of the latch member 20 and move it back to the position shown in Fig. 5 thus connecting the sash weight to the sash and allowing the sash to be raised and lowered in the normal manner.

It is also possible to use a storm sash or window screen with this device which may be inserted into the window opening from the interior 55 of the room when the sash are in the position shown in Fig. 8. In this case, the frame 34 of the storm sash or screen is positioned against the outer stop 35 and on top of the sill stop 36 provided at the bottom of the window frame. 60 Bolts 37 are provided having operating latches 38 which may be engaged in apertures provided therefor in the sill and when the sash guides are swung back to normal position the flange 9 of the cross member 5 engages sufficiently close to the screen frame 34 as to maintain it in position 65 against the stop 35, as will be understood from Figs. 7 and 8. Thus the storm windows or window screens may be inserted or removed from the window opening by first inserting the top of 70 the frame in position and then swinging the bottom of the frame to position and latching it in place. This operation may be accomplished from the interior of the room without the necessity of climbing around the outside of the building.

From the foregoing description it becomes evi-

dent that the device is very simple and efficient in operation, will not easily get out of order and provides a device which accomplishes the objects described.

Having thus fully described my invention, its utility and mode of operation, what I claim and desire to secure by Letters Patent of the United States is—

1. In a swinging window, a window frame, an inverted U-shaped sash guide hingedly connected to the top of the window frame and swingable into or out of the frame opening, a pair of sash slidably mounted in the inverted U-shaped sash guide, a sash weight on each side of the window frame, a pulley carried by each sash weight, a cord extending about the pulley, a pulley carried by each sash guide and rotatably mounted adjacent the top of the sash guide, the ends of the cord extending over the pulley, each sash being provided with a recess for the respective cord end in the edge thereof, said recess opening into an enlargement, a latch connected to each end of the cord and engaging in the recess enlargement of the respective sash, spring means carried by the latch and urging the latch into contact with the inner face of the respective sash guide, the sash guide being provided with apertures for the respective latches and the arrangement being such that as the sash are moved downwardly in the sash guides the spring means urges the ends of the latches out of the enlargement in the sash and into latching engagement in the apertures in the sash guide, said recess enlargement being provided with an angular portion arranged to engage the ends of the latches as the sash are moved upwardly in the guide and the angular face being arranged to move the latch ends out of the apertures in the sash guide and into the recess enlargements in the sash against the tension of the springs.

2. In a swinging window, a window frame, an inverted U-shaped sash guide hingedly connected to the top of the window frame and swingable into or out of the frame opening, a pair of sash slidably mounted in the sash guide, each sash being provided with a cord recess opening into an enlarged latch recess, a latch having a shank portion fitting in the cord recess and provided with a triangular shaped end fitting into the enlarged latch recess, a spring urging the triangular latch end into engagement with the inner face of the sash guide, the sash guide being provided with an aperture intermediate its ends arranged to receive a portion of the triangular end of the latch, the arrangement being such that as the sash is lowered in the sash guide the spring urges the triangular end of the latch into latching engagement in the aperture in the sash guide and the latch when so engaged being moved out of the latch recess in the sash, a cord connected to the latch and extending through the cord recess in the sash, a pulley at the top of the sash guide over which the cord extends and a sash weight connected to the cord, the latch recess in the sash being provided with an angular face and arranged so that upon upward movement of the sash the angular face engages the triangular end of the latch and moves it into latching engagement with the sash.

3. In a swinging window, a window frame, an inverted U-shaped sash guide hingedly connected to the top of the window frame and swingable into or out of the frame opening, a pair of sash slidably mounted in the inverted U-shaped sash guide, sash weights slidably mounted in the win-

dow frame, cords leading from the sash weights to the respective window sash, a latch member secured to each cord and the respective sash being each provided with a recess to receive the respective latch, the latch being positioned in the recesses of the respective sash and riding against the inner face of the adjacent sash guide, spring means urging the latch into engagement with the face of the respective sash guide, each sash guide being provided with an aperture for the latch and the arrangement being such that as the sash is lowered to a predetermined position the latch is moved into the aperture in the sash guide and the recess in the sash being so shaped that as the sash is again raised the latch is moved into the recess of the sash against the tension of the spring means.

4. In a swinging window, a window frame, an inverted U-shaped sash guide hingedly mounted at the top of the window frame and movable into or out of the frame opening, a pair of sash slidably mounted in the inverted U-shaped sash guide, a latch normally engaging each sash, a cord connected to each latch, pulleys adjacent the top of the window frame over which the cords extend, a sash weight having a pulley about which the cord extends, the arrangement being such that as the sash are lowered in the sash guides the latches are moved out of engagement with the sash and as the sash are raised the latches are automatically returned to engagement with the sash.
